schaft, Berlin, Germany, a corporation of Ger-
many

Application April 27, 1936, Serial No. 76,632
In Germany April 27, 1935

3 Claims. (Cl. 250—27.5)

It has been suggested in the prior art to design the accelerator system in Braun tubes in the form of an electron-optic immersion objective comprising two cylindrical electrodes. The first 5 one of these cylinders in this scheme is closely adjacent the cathode and it may, optionally, extend beyond it, whereas the second cylinder partly surrounds the former and extends beyond it. The second cylindrical electrode could also be 10 replaced by an inside lining of the tube.

The potential curve on the axis of such an immersion objective is shown graphically in Fig. 1 of the drawing. The abscissa of the diagram here shown corresponds to the axis of the system, while the ordinate indicates the potential U. Below the diagram is shown at the same time in 15 schematic form the system itself comprising the cathode K and the cylinders Z1 and Z2 to which suitable potentials are applied. As can be seen 20 from the diagram, a rise of potential occurs between the cathode K and the cylinder Z1. Along Z1 the shape of the potential curve is rectilinear and nearly horizontal. Between Z1 and Z2 there 25 happens another rise of potential. The lens action of the system is governed by the electrical field which arises at the said points of transition. The rectilinear shape of the potential along Z1 (and also Z2) means that the potential surfaces 30 at the said points are placed perpendicularly (or at right angles) to the axis of the system.

Now, according to this invention, in Braun tubes equipped with electrode systems of the said sort, at least the first deflection plate pair is disposed inside the first cylinder (closest to the cathode) at a point where the shape of the potential is horizontal or practically so. If the first cylinder is of sufficient size, it will be feasible to mount also the second pair of plates inside this cylinder. However, as a general rule it will be 35 suitable to place the second pair of plates posteriorly of the potential field producing the lens action.

The accommodation of the pair of plates inside the cylinder at greatest proximity to the cathode 40 offers the advantage that the deflection of the electrons happens at points of low electron velocity, and that, moreover, the deflection systems are located as close as possible to the lens which, as will be noted, is formed at points where the first cylinder passes over to the second. The 45 oscillographic tube thus becomes extremely sensitive.

An exemplified embodiment of the tube here disclosed is illustrated in Fig. 2. From the cathode 1 by the aid of the accelerative system 2, 3, an electron pattern in the form of a luminous spot is produced upon the screen 4. The cathode preferably is of the hollow type having a small and sharply bounded exit opening.

60 The cathode 1, in order to improve the image,

is surrounded by an electrode 5 in the shape of an annular disk being kept at cathode potential. Both the cylinder 2 as well as cylinder 3 have bores through which leads and supporting means for the pairs of plates 6 and 7 may be passed. 5 The plates themselves are of but reduced size, and they will thus not impair or disturb the shape of the potential seeing that the potential will be nearly constant also at the points where the plates are mounted.

I claim:

1. A cathode ray tube comprising, an envelope, an electron emitter within the envelope and positioned at one end thereof, a luminescent screen also within the envelope and positioned at the 15 end thereof opposite the emitter, a pair of cylindrical accelerating and focussing electrodes supported within the tube in the region adjacent the emitter and each longitudinally spaced therefrom and telescopically positioned relative to each 20 other so that one cylinder partially surrounds the other, said electrodes being adapted to have applied thereto positive potentials relative to the emitter to develop an electrostatic field to form the emitted electron stream into a sharply defined 25 spot focussing upon the screen, and a pair of beam deflecting electrodes positioned internally of the cylindrical electrode nearest the emitter, said deflecting electrodes being located within the cylindrical electrode in a region of electrical field 30 distribution where the shape of the potential characteristic is substantially uniform.

2. The tube claimed in claim 1 comprising in addition a second pair of beam deflecting electrodes positioned within the cylindrical electrode 35 most remote from the emitter.

3. A cathode ray tube comprising, an envelope, an electron emitter within the envelope and positioned at one end thereof, a luminescent screen also within the envelope and positioned at the 40 end thereof opposite the emitter, a pair of cylindrical accelerating and focussing electrodes supported within the tube in the region adjacent the emitter and each longitudinally spaced therefrom, said electrodes being adapted to have applied thereto positive potentials relative to the 45 emitter to develop an electrostatic field to form the emitted electron stream into a sharply defined spot focussing upon the screen, and a pair of beam deflecting electrodes positioned internally of the cylindrical electrode nearest the emitter, said deflecting electrodes being located within the cylindrical electrode in a region of electrical field 50 distribution where the shape of the potential characteristic is substantially uniform, and a second pair of beam deflecting electrodes positioned within the cylindrical electrode most remote from the emitter.
